WASHINGTON L. GILROY, OF PHILADELPHIA, PENNSYLVANIA.

Letters Patent No. 74,077, dated February 4, 1868.

IMPROVED WEATHER-STRIP.

REISSUED

The Schedule referred to in these Letters Patent and making part of the same.

Be it known that I, WASHINGTON L. GILROY, of the city of Philadelphia, in the State of Pennsylvania, have invented a new and useful Improvement in the Construction of Weather-Strips composed of wooden mouldings, or their equivalent, and India rubber, or its equivalent, for windows, doors, &c.; and I do hereby declare and ascertain said improvement as follows:

Figure 1 representing a front view of the weather-strip.

Figure 2, a transverse sectional view in the accompanying drawing.

In weather-strips made before these improvements of mine, the elastic material has been inserted in one of two ways, namely, perpendicular to the face of the wooden moulding, or in a loop or tube-form. These are well known, and we need not, therefore, more particularly describe them.

These modes of construction having serious objections to urge against them in practical use, my first improvement is to obviate them, which it most effectually does. My second improvement is in the mode of fastening the elastic medium into its wooden matrix by means of cement, instead of tacking, as has always before been done, and which is peculiarly objectionable in the slender light strips most desirable for this purpose. Instead of inserting my flat, straight elastic strips into the wood, at right angles thereto, as above remarked, I insert the same at an angle of forty-five degrees, more or less, so that the portion that projects beyond the surface of the strip acts as an elastic, readily-yielding spring that will fit surfaces that are quite unequal, and the strips themselves need not be so accurately cut or inserted to be more effective than those that do not incline.

There is an inclined saw-kerf, or narrow, deep groove cut into the wooden strip A at w, and the India rubber, B, is put therein with water-proof cement. It will be noticed that the light slim moulding would be weakened by this groove w, and that if the rubber were pinned or nailed into it, the moulding would be still more weakened; I therefore use the cement for the double purpose of more effectually uniting the rubber B and moulding A, but also as strengthening and solidifying the moulding.

Having thus fully described my improved construction of weather-strips, composed of rigid strips of wood and elastic medium, what I claim therein as my new improvement, is—

1. The insertion of a flat elastic strip into a moulding, such as above described, in an inclined position to its surface, as herein set forth.
2. I also claim affixing said elastic medium into the groove in the rigid moulding by means of water-proof cement, as and for the purposes specified.

WASH'N L. GILROY.
